UNITED STATES PATENT OFFICE.

FRANK H. HASTINGS, OF ST. JOHNSBURY, VERMONT.

DOOR LATCH.

Application filed March 20, 1920. Serial No. 367,316.

To all whom it may concern:

Be it known that I, FRANK H. HASTINGS, a citizen of the United States, residing at St. Johnsbury, in the county of Caledonia and State of Vermont, have invented new and useful Improvements in Door Latches, of which the following is a specification.

The invention relates to doors and other forms of closures and more particularly to the doors on motor and other vehicles and has for an object to provide a latch therefor.

Among other features the invention comprehends a simple form of latch or lock for use on automobile doors and the like to secure the same in locked relation to the body or frame of the vehicle with means for readily actuating the latch to unlock the door so that it can be easily opened. To this end the invention comprehends spring actuated elements which will tend to normally prevent the door from rattling when in closed position, the lock being adapted for use in connection with doors on open or closed vehicles, as the case may be.

In the further disclosure of the invention reference is to be had to the accompanying drawings constituting a part of this specification, in which similar characters of reference denote corresponding parts in all the views, and in which—

Figure 1 is a fragmentary vertical longitudinal sectional view taken through an automobile door and a portion of the frame showing the use of my device on an automobile door of an open body.

Figure 2 is a fragmentary horizontal sectional view through the door and frame as well as through parts of the improvement, the dotted lines indicating the position of the latch member when a pressure has been exerted upon the operating rod to unlatch the door.

Referring more particularly to the views the numeral 10 indicates an automobile door and 11, the frame for the door. The door is hinged, the opposite sill 13 providing what may be termed an abutment for the door. Suitably secured in the sill 13 is a spring arm 14 having the end 15 fitted into the sill and the end 16 normally spaced from the sill and formed in a Z-shape head, providing a nose 17 and a recessed portion 18. A push rod 19 is mounted in the door and at its upper end carries a handle piece 20 which normally fits almost flush with the top of the

door, the top being grooved or gouged out to receive the piece. A spring 21 encircles the rod 19 and has one end abutting against a part of the frame work of the door as at 22, the other end of the spring being secured to the rod in any suitable manner so that the spring will tend to normally hold the rod in its uppermost position, so that a head 23 on the lower end of the rod will normally fit in a seat 24 of a plate 25, the latter being secured to the edge 12 of the door with the rod 19 passing through an opening 26 in the plate. The plate is also formed with a strike 27 having an inclined face 28 and by reference to Figure 1, it will be seen that when the door is closed the strike will ride over the spring arm 14, pressing its free end against the sill until the strike is passed beyond the extension 17, after which the free end of the spring arm will spring out so that the inclined face 28 will fit into the recessed portion 18.

A downward push exerted on the handle piece 20 actuates the push rod against the action of the spring 21, causing the head 23 of the rod to be projected against the head of the spring arm 14 thus moving it toward the sill and out of the path of the strike 27 so that the door can now be swung into an open position, it being of course understood that the action of the push rod against the spring arm will cause the inclined portion or face of the head of the spring arm to ride upon the inclined face of the strike and thus bring about a slight inward movement of the door before it is released.

From the foregoing description it will be seen that the latch described is of a simple construction; consists of few parts that cannot readily get out of order and that by having the handle piece 20 fitted close to the upper edge of the door, the usual unsightly handles now generally found on the inside or outside of automobiles, are entirely done away with and my form of handle piece will present a neat and effective appearance without destroying the appearance of the automobile body.

As disclosed in the horizontal sectional view, the nose 18 of the Z-shaped latch 17 is received against the inner face 27 of the keeper member and is held in frictional engagement therewith by its own resiliency and thus the movement of the door in one direction is prevented. The nose of the latch is also held in such position by the spring

influenced push rod, the head of the latter contacting with the body 17 of the latch. The frictional engagement between the head of the push rod and the latch is sufficient 5 to prevent the accidental swinging of the door in a second direction. If the operator exerts a determined pressure upon the push rod to permit of the opening of the door, such pressure will cause the bowing of the 10 body 17 of the spring latch, causing the nose 18 thereof to be brought out of engagement with the inclined face 27 of the keeper, and also forcing the latch bodily into the pocket provided therefor, thus permitting the door 15 to freely open. When relieved of pressure, the latch will assume the position shown in the said horizontal sectional view and the swinging of the door to closed position will again bring the nose 18 into engagement 20 with the inclined face 27 of the keeper member, and the spring influenced rod will again have its head contacting the body of the latch, as disclosed in the full lines in the said sectional view.

25 Having described my invention, I claim—
1. A means for latching a door to the

abutment sill of a frame on which the door is hinged, comprising a spring arm secured to the sill of the frame and having the head end thereof normally spaced from the sill, 30 a strike on the door and projecting therefrom to lock with the head of the spring arm and a push rod on the door and movable to have an end thereof engage the spring arm and move the same out of engagement 35 with the strike.

2. In combination with a frame and a door hinged to the frame, of means for latching the door to the frame, comprising a spring arm secured to the sill of the frame and having 40 the head end thereof normally spaced from the sill, a strike on the door and projecting therefrom to lock with the head of the spring arm, a push rod on the door and movable to have an end thereof engage the spring arm 45 and move the same out of engagement with the strike and a handle piece for operating the push rod, said handle piece being carried on one end of the push rod and simulating the lines of the upper edge of the door. 50

In testimony whereof I affix my signature.
FRANK H. HASTINGS.
